Russel Wheeler and Stephen A. Bailey of Utica, N.Y.
Letters Patent No. 1623, dated Aug. 5, 1862,

The schedule referred to in the Letters Patent and making part of the same.
To all whom it may concern,

Be it known that we, Russel Wheeler & Stephen A. Bailey of the City of Utica in the County of Oneida, and State of New York, have made a new and improved design for a Parlor Stove; and we do hereby declare that the following is a full and exact description thereof, reference being had to the accompanying drawings.

The nature of our design consists in a new form or design for a parlor stove as represented in the accompanying drawings.

To enable others skilled in the art to make and use our design we will proceed to describe its form design and construction.

The lower section I, is of cast iron designed and ornamented as represented by B. C. D. E and G, in the accompanying drawings. It represents the design of the legs. D which is the form of a sprig represents the ornament on ends of the lower section of the stove. C, represents ornament in centre E and G, represent plain mouldings and B. B, represent ornamental mouldings.

The upper section I, is of cast iron designed as represented in the accompanying drawings and ornamented by ornamental mouldings A, A and B. B.

What we claim as our invention and design and desire to secure by Letters Patent, are the form, ornaments and design of a Parlor Stove as above described and represented.
